PHILIP T. ROBIN AND CARL J. SCHELOSKE, OF ERIE, PENNSYLVANIA, ASSIGNEES TO
G. H. WILLIAMS COMPANY, OF ERIE, PENNSYLVANIA, A CORPORATION OF PENNSYLVANIA

EARTH HANDLING STRUCTURE

Application filed December 28, 1929. Serial No. 417,204.

The present invention relates to an earth handling structure, particularly to a construction of buckets and dippers having sides and bottom with a cutting lip along its front edge. It is particularly adaptable to drag line buckets and the invention is illustrated as applied to such a bucket. It is desirable with such a bucket to have the front corners of the bucket rounded. Such a construction, however, if formed entirely of the plates of which the bucket is usually fashioned requires heavy forming tools and expensive equipment. With the present invention this corner is formed of a separate piece and inserted in a gore between the front edges of the sides and bottom plates and this permits of the forming of the bucket as a whole without flanging, or forming operations. It is also desirable to give to the lip a slight downward curve. This involves also a bending of the bottom plate to form this curve. Where the lip is formed separately the flat plate forming the bottom can be readily drawn down to this shape as it is riveted to the lip, thus avoiding a forming operation as to this. In this manner it is possible to fashion a bucket having the desirably shaped front end without a heavy forming operation. Features and details of the invention will appear from the specification and claims.

A preferred embodiment of the invention is illustrated in the accompanying drawings as follows:—

Fig. 1 shows a plan view of the bucket.

Fig. 2 a section on the line 2—2 in Fig. 3 looking toward the front of the bucket.

Fig. 3 a side elevation of the bucket.

Fig. 4 a section on the line 4—4 in Fig. 3, looking toward the rear of the bucket.

Fig. 5 a detached view of the corner piece.

1—1 mark the sides of the bucket. These sides follow the general contour of the sides of the bucket and the rounded rear ends. A bottom plate 2 is rolled up at its rear end

45 forming the back 3 of the bucket and the rear portions of the sides and bottom plates are welded together at 4. A cutting lip 5 formed of cast steel is arranged along the front of the bucket. This has a shoulder 6 against which the bottom plate abuts and is provided

with teeth 7 in the usual manner. The teeth 7 have the rearwardly extending shanks 8 and rib plates 9 extend from the shanks along the bottom plate to the back of the bucket.

The bottom plate is cut away along its sides adjacent to the front at 10 and the side plate is similarly cut away along its bottom edge adjacent to the front along the line 11 as shown in Fig. 2. These cutting edges form a gore at the front corner of the bucket. This gore is filled by a cast corner piece 12 which has a conically curved surface, the point of the gore terminating at the juncture of the side and bottom. The corner piece 12 has a shoulder 13 which engages the cut-away edge 11 and is extended with an overlapping flange 14 which overlaps the side 1 and to which it is secured by rivets. The corner piece also has a shoulder 15 which engages the cut-away portion of the bottom plate and is provided along the bottom with an overlapping flange 16 which is secured to the bottom plate by rivets 17. The corner plate has an extension 18 which is of the same thickness as the side and bottom plates and continues the closure for the gore to the shoulder 6 of the lip and forms the connection between the corner piece and the lip as well as the auxiliary side plates 1a.

The cutting lip 5 is slightly downwardly curved at 19 and the bottom plate 1 has the initial flat shape, as indicated at 20 in Fig. 4. It is drawn down to the curve of the lip as it is riveted in place, thus avoiding the necessity for any forming action as a preliminary to the fabrication of the bucket. In this way a very rigid and substantial structure is provided. The front lip and corners have the desirable rounded surfaces and the lip the usual downward curve and the connection of the sides and bottom toward the rear is a simple welding operation and the bottom can be readily fashioned in an ordinary set of rolls.

What we claim as new is:—

1. In an earth handling structure having a cutting edge, the combination of sides and a bottom forming a gore between their edges adjacent to and extending rearwardly from the cutting edge; and corner pieces inserted

in the gores, said corner pieces having flanged edges overlapping the sides and bottom.

2. In an earth handling structure, the combination of sides and a bottom forming a gore between their edges; and corner pieces inserted in the gores, the corner pieces having conical surfaces continuing and joining the sides and bottom.

3. In an earth handling structure, the combination of sides and a bottom forming a gore between their edges; and corner pieces inserted in the gores, the corner pieces having conical surfaces continuing and joining the sides and bottom, said corner pieces having flanges overlapping the sides and bottom.

4. In an earth handling structure, the combination of sides and a bottom forming a gore between their edges; a cutting lip having a shoulder against which the bottom abuts; and corner pieces arranged in the gores, said corner pieces having conical surfaces continuing and joining the sides and bottom.

25 5. In an earth handling structure, the combination of sides and a bottom forming a gore between their edges; a cutting lip having a shoulder against which the bottom abuts; and corner pieces arranged in the gores, said corner pieces having conical surfaces continuing and joining the sides and bottom, said pieces abutting the shoulder on the lip.

6. In an earth handling structure, the combination of sides and a bottom forming a gore between their edges; a cutting lip having a shoulder against which the bottom abuts; and corner pieces arranged in the gores, said corner pieces having conical surfaces continuing and joining the sides and bottom, said pieces abutting the shoulder on the lip and having flanges overlapping the bottom and sides.

7. In an earth handling structure, the combination of sides and a bottom forming a gore between their edges adjacent to the front of the structure, the edges of the sides and bottom being directly secured together in a direct joint; and corner pieces closing the gores.

50 8. In an earth handling structure, the combination of sides and a bottom forming a gore between their edges adjacent to the front of the structure, the edges of the sides and bottom being directly secured together in a direct joint; corner pieces closing the gores; and a lip at the front of the structure, said lip being curved downwardly and the bottom being flat at the rear and sprung to the shape of the lip at the front.

In testimony whereof we have hereunto
set our hands.

PHILIP T. ROBIN.
CARL J. SCHELOSKE.
